United States Patent Office

Des. 224,326
Patented July 18, 1972

224,326

SEAT FOR PLAYGROUND APPARATUS

Ronald L. Ewers, Hillsdale, Mich., assignor to Game
Time, Inc., Litchfield, Mich.

Filed Mar. 18, 1971, Ser. No. 125,902

Term of patent 14 years

Int. Cl. D21—03

U.S. Cl. D34—5

FIG. 1

FIG. 3

FIG. 2

FIG. 4

FIG. 5

FIG. 1 is a right side elevational view of a seat for playground apparatus showing my design, the left side appearing as the mirror image thereof,

FIG. 2 is a top plan view,

FIG. 3 is a front elevational view,

FIG. 4 is a rear elevational view, and

FIG. 5 is a bottom view.

I claim:

The ornamental design for a seat for playground apparatus, substantially as shown and described.
